UNITED STATES PATENT OFFICE

113,541

DESIGN FOR A WHEELED TOY FIGURE

Charles H. Pajeau, Evanston, Ill., assignor to The Toy Tinkers, Inc., Evanston, Ill., a corporation of Illinois

Application December 15, 1938, Serial No. 81,789

Term of patent 7 years

To all whom it may concern:

Be it known that I, Charles H. Pajeau, a citizen of the United States, residing at Evanston, Cook County, Illinois, have invented a new, original, and ornamental Design for a Wheeled Toy Figure,
of which the following is a specification, reference being had to the accompanying drawing, forming part thereof.

In the drawing:

I claim:

The ornamental design for a wheeled toy figure,
as shown.

CHARLES H. PAJEAU.
